US00D754857S

(12) United States Design Patent
Grant et al.(10) Patent No.: US D754,857 S
(45) Date of Patent: * Apr. 26, 2016(54) BONE PLATE

- (71) Applicant: NuVasive, Inc., San Diego, CA (US)
- (72) Inventors: Chad Grant, Escondido, CA (US); Eric Dasso, Carlsbad, CA (US); Robert German, San Diego, CA (US); Richard Mueller, Chapel Hill, NC (US); Ryan Donahoe, San Diego, CA (US)
- (73) Assignee: NuVasive, Inc., San Diego, CA (US)
- () Term: 14 Years
- (21) Appl. No.: 29/446,441
- (22) Filed: Feb. 22, 2013

Primary Examiner — Susan Hattan*Assistant Examiner* — Charles Hanson*(74) Attorney, Agent, or Firm* — Jennifer Russell(57) CLAIM

The ornamental design for a bone plate, substantially as shown and described.

DESCRIPTION

FIG. 1 is a perspective view of a bone plate showing our new design; and,

FIG. 2 is a bottom view thereof.

The broken line showing is included for the purpose of illustrating environment and forms no part of the claimed design.
